UNITED STATES PATENT OFFICE.

ROBERT J. WATTS AND SQUIRE COOPER, OF SHELBYVILLE, INDIANA.

WIRE-FENCE MACHINE.

SPECIFICATION forming part of Letters Patent No. 361,561, dated April 19, 1887.

Application filed October 7, 1886. Serial No. 215,578. (No model.)

To all whom it may concern:

Be it known that we, ROBERT J. WATTS and SQUIRE COOPER, citizens of the United States, residing at Shelbyville, in the county of Shelby 5 and State of Indiana, have invented certain new and useful Improvements in Wire-Fence Machines; and we do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 Our invention relates to a wire-fence machine, the object thereof being to facilitate the twisting of the wires about the slats in the construction of fences; and it consists in the construction and arrangement of parts, as will be 20 hereinafter fully set forth and claimed.

In the annexed drawings, illustrating our invention, Figure 1 is a vertical side elevation of our improved wire-fence machine, showing the 25 whole of the twisting mechanism. Fig. 2 is a side elevation taken at right angles to the elevation of Fig. 1, with a portion of the box or casing broken away to expose the inner mechanism; and Fig. 3 is a sectional plan view.

Like letters of reference designate like parts 30 in all the figures.

The frame of our machine consists of a vertical rectangular box or casing, which is inclosed on three sides, as A A and B, and open on the remaining side, and which is supported 35 on a foot-piece or base, C, of suitable construction, to assist in the easy locomotion of the machine from point to point in the field during its operation. A handle, K, secured to the box assists in moving it. This casing is provided, 40 at convenient distances from the top and bottom, with horizontal arms D, consisting, preferably, of single pieces of metal bent into the form shown in the drawings, with an outer loop or notch to receive and hold a slat while the 45 wires are being twisted about it.

Within the casing A are situated the driving-wheels E, which are secured on short spindles a that are journaled in the side B of the casing. The number of these wheels varies according 50 to the number of wires in the fence; but four is a convenient number, as depicted on the drawings. These wheels consist of a rear plate,

a circular band, b, provided on its exterior peripheral surface with a series of sprockets, and a bevel-gear, c, located within the band b and rigidly affixed to the spindle a, on which also the rear plate is fastened. The several wheels 55 E are connected and moved simultaneously by means of a chain, F, which passes around them all, a rotary motion being imparted to one of the wheels—as the upper one—by a crank secured on the extremity of the spindle a, which is extended through the casing for the purpose.

Adjacent to each of the wheels E is a horizontal shaft, G, extending between the sides A A and projecting outwardly through the same. Said shafts carry bevel-gears H, which mesh with the bevel-gears c, and near the extremities of the shafts, outside of the walls A A, they are provided with slotted twisting-wheels I, 70 made fast on the shaft by means of suitable devices—such as set-screws—passing through collars that are integral with the wheels I. The wheels I are further provided with inwardly-projecting tubular rims d, that are received into 75 similarly-shaped holes in the sides A, and which form the journals on which the shafts G revolve.

The sides A A are provided with horizontal slots e e, extending from the edge inward 80 to the point where the shafts G are journaled; also, the bevel-gears H have oppositely-located slots passing from the periphery to within a short distance of the shaft G. The slots in the twisting-wheels I are properly 85 aligned with the slots in the gears H, and the wheels I are so located as to enable them at a certain point in their rotation to bring their slots into coincidence with the slots c in the sides. The edges of the sides A A are preferably 90 furnished with rods f, held in place by the rings g and serving to cover the slots e and prevent the wires from slipping out.

The operation of the machine may be briefly described as follows: A slat is first placed in 95 position in the arms D D. The rotative mechanism being so placed that the several slots of the twisting-wheels, the bevel-gears, and the sides A A may be properly in line with each other, the pairs of wires are passed through 100 said slots and allowed to remain in them. The operator next grasps the handle of the crank and revolves it as many times as he desires to twist the wires. The machine is then moved

forward a suitable distance, another slat is put in place, and by a reverse motion of the crank the wires are again twisted, and thus the operation proceeds.

5 Having thus described our invention, what we claim as new, and desire to secure by Letters Patent, is—

1. The combination, with a box or casing, of the driving-wheels journaled therein, each composed of a sprocketed rim and an interiorly-located gear, the connecting-chain for said driving-wheels, and the twisting devices journaled in the casing adjacent to the driving-wheels and each comprising a shaft carrying slotted 15 wheels near each end, and a gear that meshes with the gear of the adjacent driver, substantially as described.

2. In a wire-fence machine, the combination of the box or casing slotted at *e e*, the twisting 20 devices consisting of shafts *G*, carrying at either end the slotted wheels *I*, having tubular rims *d*, by means of which said twisting devices are journaled in the casing, and suitable actuating mechanism for the twisters, as herein 25 specified and shown.

3. In a wire fence machine, the combination of the slotted casing, the twisting devices journaled therein and having gears *H*, and the driving-wheels consisting of sprocketed rims *b*, and interior bevel-gears, *c*, that mesh with the gears *H*, the series of driving-wheels being connected by a chain, *B*, so that the actuation of one will drive the series, substantially as described. 30

4. The combination of the casing consisting of sides *A A* and *B*, the sides *A A* being slotted at *e e*, as shown, the vertical rods *f f*, secured to the edges of the sides *A A*, the twisting devices journaled in the casing and actuated substantially as described, and the slat-supporting arms, all arranged in the manner 40 and for the purposes set forth. 35

In testimony whereof we affix our signatures in presence of two witnesses.

ROBERT J. WATTS.
SQUIRE COOPER.
